US00D378081S

United States Patent [19]

Antonczak et al.

[11] Patent Number: Des. 378,081

[45] Date of Patent: **Feb. 18, 1997

[54] **CONFIGURABLE MULTI-PRODUCT ELECTRONICS ENCLOSURE**

[75] Inventors: **Michael J. Antonczak**, Aptos; **Philip G. Yurkonis**, Campbell; **Michael S. Dann**, Mountain View; **Paul S. Montgomery**; **Herbert H. F. Pfeifer**, both of San Francisco; **James G. Ammon**, San Jose, all of Calif.

[73] Assignee: **Sun Microsystems, Inc.**, Mountain View, Calif.

[**] Term: **14 Years**

[21] Appl. No.: **8,431**

[22] Filed: **May 10, 1993**

[52] U.S. Cl. **D13/184**

[58] Field of Search D13/184; D14/107, D14/101; 361/724, 725, 727, 728, 729

[57] **CLAIM**

The ornamental design for a configurable multi-product electronics enclosure, as shown and described.

DESCRIPTION

FIG. 1 is a front and upper right perspective view of a configurable multi-product electronics enclosure showing the first embodiment of our new design;

FIG. 2 is a front elevation view of a configurable multi-product electronics enclosure showing the second embodiment our new design. All other plan and elevation views are the same as the first embodiment;

FIG. 3 is a front elevation view of the first embodiment;

FIG. 4 is a front elevation view of a configurable multi-product electronics enclosure showing the third embodiment our new design. All other plan and elevation views are the same as the first embodiment;

FIG. 5 is a right side elevation view of the first embodiment, the left side being a mirror image;

FIG. 6 is a rear elevation view of the first embodiment;

FIG. 7 is a rear elevation view of a configurable multi-product electronics enclosure showing the fourth embodiment our new design. All other plan and elevation views are the same as the first embodiment;

FIG. 8 is a top plan view of the first embodiment;

FIG. 9 is a bottom plan view of the first embodiment;

FIG. 10 is a rear and upper left perspective view of the first embodiment; and,

FIG. 11 is a rear and upper left perspective view of the fourth embodiment.
